UNITED STATES PATENT OFFICE.

RICHARD BAILLARGEON, OF PORT HURON, MICHIGAN, ASSIGNOR OF ONE-HALF TO JOHN ASMAN, OF PORT HURON, MICHIGAN.

BRUSH-HANDLE.

No. 839,088.

Specification of Letters Patent.

Patented May 26, 1908.

Application filed January 28, 1908. Serial No. 413,674.

To all whom it may concern:

Be it known that I, RICHARD BAILLARGEON, a citizen of the United States, residing at Port Huron, in the county of St. Clair and State of Michigan, have invented new and useful Improvements in Brush-Handles, of which the following is a specification.

This invention relates to improvements in brush handles for window cleaners and the like.

The main object of the invention is to provide a telescopic extensible handle which is simple of construction and adapted to be manufactured at a low cost and to permit ready and convenient adjustment of the brush, mop or scraper carrying section, whereby the handle as a whole may be made of any length within its extreme limits to suit the height at which the work is being done, thus obviating the annoyances and inconveniences arising from the use of a heavy and lengthy handle at a point low down upon the window.

A further object of the invention is to provide a hollow handle proper which may be employed in connection with window cleaners of the type in common use, and which is of such a form and construction as to be readily and conveniently manufactured.

With these and other objects in view, the invention consists of the features of construction, combination and arrangement of parts hereinafter fully described and claimed, reference being had to the accompanying drawings, in which:

Figure 1 is a top plan view of a window cleaner embodying my invention. Fig. 2 is a vertical longitudinal section through the hollow section of the handle, showing the rod section in elevation. Figs. 3 and 4 are cross-sections on the lines 3—3 and 4—4 of Fig. 1. Fig. 5 is a top plan view showing a modification.

Referring to the drawing, 1 designates the operating rod or handle of a window cleaner of any ordinary construction, upon the outer end of which rod or handle is fitted a work head 2, which may be in the form of a brush head, mop head or scraper, as desired. The cleaner as thus constructed is designed for use in connection with a hollow handle 3 adapted to receive the rod 1, which is slidably adjustable therein to contract and extend the handle as a whole. For convenience of description, the handle of the device will be

hereinafter described as consisting of a hollow stationary section and an extensible rod section, as the two coöperate to form the telescopic handle for the brush head 2.

The hollow section 3 is preferably longitudinally divided, being formed of two substantially semicylindrical sections 4 and 5, thus adapting said hollow section of the handle to be conveniently manufactured by ordinary types of wood-working machines. The meeting edges of the sections 4 and 5 at one side are recessed for a portion of the length thereof to provide a longitudinal slot 6, and such sections 4 and 5 are united at their end portions by caps 7 and 8 secured in any suitable manner thereto to hold the sections firmly united, the cap 8 being apertured to form a ferrule and provide a passage for the rod 1. At the ends of the slot 6 the sections 4 and 5 are further reinforced and connected by suitable means, such as a clamping band 9 and a cross-bolt 10, for which latter a band 11 similar to the band 9 may be substituted, as shown in Fig. 5. The sections of the hollow handle 3 are further connected and reinforced between the terminals of the slot 6 by split bands or clips 12, the end portions 13 of which are bent to lie in recesses 14 in the surface edges of the slot 6 and are secured therein by nails or other suitable fastenings, thus holding them firmly in position. The end caps, bands and clips will thus securely unite the portions or sections of the hollow handle to form a sleeve or casing for the rod section 1, which is substantially coextensive in length therewith.

It will be understood from the foregoing description that the rod section 1 may be adjusted in and out of the hollow section 3 to render the handle of the work head 2 of any suitable length within the range of adjustment of the section 1, and when the latter is forced fully into the hollow section 3 the length of the handle as a whole will but slightly exceed the length of said section 3. In order to secure the rod section 1 in adjusting position a clamping device is provided comprising a bolt or threaded stem 15 carried by said rod section and movable in the longitudinal slot 6. The stem projects beyond said slot and through a clamping plate 16 bridging across the slot and adapted to bear upon the side walls thereof, an adjusting nut 17 being provided upon the stem 110

by which the clamping plate may be loosened or tightened to clamp or free the rod. By disposing the ends of the clips 12 within recesses in the edge walls of the slot 6, it will be noted that the same will offer no interference to the free movement of the clamping plate. If desired, the inner end of the rod section 1 may be bifurcated or formed with a longitudinal slot 18 to receive the bolt 10, by which such end of the rod section may slide back of the bolt into the butt section of the handle, thus allowing a rod section of maximum length to be employed.

It is well known that window cleaning devices of ordinary construction are necessarily provided with comparatively long handles in order to permit the work head to be brought into contact with the upper portions of high store windows, and that in using devices of this kind in cleaning the lower portions of such windows difficulties and annoyances are found in the operation of the cleaner and amount of pavement surface occupied owing to the long length of the handle. These objections and difficulties are overcome by the use of my improved telescopic handle, which is adjustable to different lengths to suit the convenience in working upon portions of the window at different elevations. The hollow handle section 3 may be employed in connection with the rod section 1 of cleaners in common use by simply cutting off a portion of the rod section of the cleaner which is to be used, as will be readily understood. By employing the band 11 shown in Fig. 5 in place of the cross-bolt 10, the necessity of bifurcating the rear end of the rod section is

avoided, but either construction may be advantageously employed. By the use of the means employed for connecting the semi-cylindrical halves of the hollow section 3, such section may be easily and economically manufactured without necessitating the employment of special wood-working machines.

It will be understood that the longitudinal guide slot in the handle may be made at any other point other than by providing the meeting or joint edges of the sections with recesses.

Having thus fully described the invention, what is claimed as new is:—

In a device of the character described, the combination of a rod, a sleeve to receive the same, said sleeve comprising a pair of semi-cylindrical sections recessed in two of their adjacent meeting edges to provide a longitudinal slot, the walls of the slot having spaced transverse recesses, caps connecting the ends of said sections, means connecting the sections at the ends of the slot, clips engaging the sections between the ends of the slot and having their end portions fitted and secured within said transverse recesses, and a clamping device carried by the rod and movable in the slot and adjustable for engagement with the walls thereof to secure said rod in adjusted position to the sleeve.

In testimony whereof I affix my signature in presence of two witnesses.

RICHARD BAILLARGEON.
